(57) **CLAIM**

The ornamental design for an combined ice cream scoop and attachment, as shown and described.

DESCRIPTION

FIG. 1 is a front perspective view of an combined ice cream scoop and attachment showing my new design according to a first embodiment;

FIG. 2 is a front perspective view of an combined ice cream scoop and attachment showing my new design according to a second embodiment;

FIG. 3 is a front perspective view of an combined ice cream scoop and attachment showing my new design according to a third embodiment;

FIG. 4 is a front perspective view of an combined ice cream scoop and attachment showing my new design according to a fourth embodiment;

FIG. 5 is a front elevation view of the combined ice cream scoop and attachment of the first, second, third, and fourth embodiments, shown separately for clarity of illustration;

FIG. 6 is a rear elevation view of thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a front perspective view of the attachment of the first embodiment, shown separately for clarity of illustration;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a front perspective view of the attachment of the second embodiment, shown separately for clarity of illustration;

FIG. 18 is a front elevation view thereof;

FIG. 19 is a rear elevation view thereof;

FIG. 20 is a left side elevation view thereof;

FIG. 21 is a right side elevation view thereof;

FIG. 22 is a top plan view thereof;

FIG. 23 is a front perspective view of the attachment of the third embodiment, shown separately for clarity of illustration;

FIG. 24 is a front elevation view thereof;

FIG. 25 is a rear elevation view thereof;

FIG. 26 is a left side elevation view thereof;

FIG. 27 is a right side elevation view thereof;

FIG. 28 is a top plan view thereof;

FIG. 29 is a front perspective view of the attachment of the fourth embodiment, shown separately for clarity of illustration;

(Continued)

FIG. 30 is a front elevation view thereof;
FIG. 31 is a rear elevation view thereof;
FIG. 32 is a left side elevation view thereof;
FIG. 33 is a right side elevation view thereof; and,
FIG. 34 is a top plan view thereof.
